CLAIM

The ornamental design for a motorcycle passenger peg arm, as shown and described.

DESCRIPTION

FIG. 1 is a perspective view of the motorcycle passenger peg arm of the present invention.

FIG. 2 is a front side view thereof.

FIG. 3 is a rear side view thereof.

FIG. 4 is a top side view thereof.

FIG. 5 is a bottom side view thereof.

FIG. 6 is a first end view thereof; and,

FIG. 7 is a second end view thereof, opposite the first end view.

The mounting structures for the motorcycle passenger peg arm shown in broken lines form no part of the claimed design.
